Fig. 3

Fig. 4

Fig. 5

FIG. 1 is a perspective view of the chair showing the design of my invention;

FIG. 2 is a front elevational view of the chair without the base portion shown;

FIG. 3 is a side elevational view of the chair illustrated in FIG. 2;

FIG. 4 is a top plan view of the chair illustrated in FIG. 1; and

FIG. 5 is a fragmentary side elevational sectional view of the chair taken on plane V—V of FIG. 2.

The dominant feature of my design resides in the portion shown in full lines on the drawing and is characterized by the recess between the rear portion of the seat and the main portion of the back of the chair as particularly shown in FIGURES 1, 2 and 5.

The side of the chair not shown is like the side shown, while the back is conventionally plain.

I claim:

The ornamental design for a chair, substantially as shown and described.
